UNITED STATES PATENT OFFICE

152,831

DESIGN FOR A DISH OR THE LIKE

Joseph G. Saba, Brookline, Mass.

Application June 10, 1947, Serial No. 139,570

Term of patent 3½ years

(Cl. D36—4)

To all whom it may concern:

Be it known that I, Joseph G. Saba, a citizen of Syria, residing in Brookline, in the county of Norfolk and State of Massachusetts, have invented a new, original, and ornamental Design for Dishes or the like, of which the following is a specification, reference being had to the accompanying drawing, forming part thereof.

In the drawing:

Figure 3 is a fragmentary plan view of a portion of the dish or the like on an enlarged scale.

The dominant features of my design reside in the part drawn in full lines as shown.

I claim:

The ornamental design for a dish or the like, as shown and described.

JOSEPH G. SABA.
